[57] ABSTRACT

The invention relates to electrical apparatus of substantial size which includes an outer container and a unit insertable in the container which can be readily withdrawn for the purposes of repair or inspection. The insertable unit consists of an oil-cooled lower part and an upper control part. The container has an internal shoulder which is engaged by the upper control part of the unit when the unit is inserted in the container. Struts pivotally connected to the lower end of the unit serve to guide the unit during its withdrawal from the container and to serve as support legs for the unit after it is withdrawn. When the unit is in its withdrawn position the struts rest on the internal shoulder of the container. The struts fold under the unit when it is inserted into the container.

HOUSING ASSEMBLY FOR OIL COOLED ELECTRICAL APPARATUS

The invention relates to an electrical apparatus, and in particular to a control apparatus with an oil-cooled power part and a control part disposed thereabove, in which an insertable unit carrying electrical components is adapted to be withdrawn from a casing which can be opened at the top.

An apparatus of this kind is disclosed in German Patent 1,808,887. Since the insertable unit accommodated within the casing is not accessible, it must be withdrawn from the casing upwardly and placed on a support for the purpose of repair, inspection or the like. This is generally not possible at the place where the apparatus is installed since suitable surfaces for depositing the insertable unit are not available and in the case of oil-cooled items of apparatus, contamination would be caused by the dripping oil.

The object of the invention is to provide an electrical apparatus of the initially described kind which can be repaired and inspected on site without difficulty.

According to the invention this object is achieved by each of two oppositely disposed side-walls of the casing having a shoulder on its inner surface, and by the insertable unit carrying at its lower end stays which can be displaced in both directions between a position within these side-walls and a splayed position in which their span exceeds the distance between the side-walls.

In this construction the casing itself is used for supporting the withdrawn unit. The stays hold the insertable unit at such a level that all the electrical components are readily accessible. In the case of oil-cooled items of apparatus the oil is able to drip back directly into the casing.

It is particularly advantageous if each stay can be pivoted about an axis parallel to the shoulders, can be swung flat against the bottom of the insertable unit in the normal position, and from there can be pivoted downwards and outwards through an angle of somewhat more than 90°. Such swingable stays occupy no additional space in the normal position, but have a certain length which enables the insertable unit to be supported, when withdrawn, at a certain distance above the shoulders. This means that in the inspection position the insertable unit is located at a distance above the casing or that the shoulders can be provided at a position downwardly removed from the top of the casing by a selectable distance.

In particular the distance separating the shoulders from the top of the casing may be approximately equal to the length of the stays.

This is of particular importance when the shoulders form the lower limit of a wider part of the casing that, in the normal position, accommodates a portion of the insertable unit that has a greater cross-section than the portion disposed therebelow and that rests on the shoulders. This results in a space-saving construction in which the shoulders are specifically designed to receive the weight of the insertable unit.

The stays are advantageously subjected to a spring force which displaces them outwardly. If the insertable unit is lifted, the stays automatically move into the splayed position in which they can support themselves on the shoulders.

Further, guides intended to engage the stays can be provided in the casing, these guides displacing the stays

when the insertable unit is lowered into the normal position.

With spring-loaded swingable stays it suffices to use, as the guides, inclined rails which extend from a point close to the shoulders to a point close to the middle of the base.

In order to enable the stays to be independent of the guides when these are supported on the shoulders, it is preferred that the stays should assume a predetermined

10 outer splayed position in which the lower ends of the stays rest approximately at the points where the shoulders merge with upper portions of the walls, and that these portions of the walls should slightly overlap the insertable unit in its raised position, for the purpose of 15 forming a lateral abutment. When the insertable unit is displaced laterally against one of the abutments, the stay on the opposite side is completely released from its shoulder and can be held in this position by slightly inclining the insertable unit. By lateral displacement of 20 the insertable unit to bring it against the second abutment, it is also possible to remove the second stay from its shoulder.

In accordance with a further feature of the invention, 25 at least one side-wall of the casing may have, above the shoulder, an opening of which the size exceeds the cross-section of a multiple contact plug intended for use with the apparatus, and this opening may be closed by a cover plate which carries water-tight cable-inlet bushes. This opening enables operations to be carried 30 out on the stays independently of the automatic return movement. It offers the further advantage that after removal of the cover plate, the multiple contact plug can be completely withdrawn from the casing so that it does not interfere with the lifting of the insertable unit.

35 Particular advantage accrues if the insertable unit has handles at its upper part. Generally, no crane or equivalent means is available at the place where the apparatus is installed. Since the insertable unit has only to be raised through a certain distance, these handles suffice 40 for the purpose even if the apparatus is relatively heavy.

In one form of construction, the insertable unit has 45 at its upper part plug-in printed-circuit boards which are secured and guided by means of a swingable cover, and the handles are formed as an extension of the frame of the swingable cover, which frame is held in its closed position by a robust locking means suited to the weight of the insertable unit.

50 Each shoulder preferably forms the upper ends of cooling ribs which project outwardly from each sidewall. This feature enables a relatively small thickness of wall to be used and despite this to provide sufficient stability for supporting the weight of the inserted unit.

55 The invention will now be described in greater detail by reference to an embodiment illustrated diagrammatically in the annexed drawing, in which:

FIG. 1 shows a diagrammatic cross-section through the apparatus of the invention in its normal position and with the cover removed,

FIG. 2 shows the apparatus of the invention in the raised position for inspection, and, in dotted lines, an intermediate position,

FIG. 3 is a side view of the upper part of the insertable unit seen in the direction of the arrow A of FIG. 2,

FIG. 4 shows on a greater scale a section through the left-hand upper part of the casing seen in FIG. 1, and

FIG. 5 is a side view of a stay in the guide.

The casing 1 consists of two shorter side-walls 2, two longer side-walls 3 and a base 4. An insertable unit 5 has a lower power part 6 and an upper control part 7 of greater cross-section. In the normal position (FIG. 1), the latter rests with its lower edge on shoulders 8 on each of the side-walls 2 and 3. The side-walls are provided with cooling ribs 9, the positions of which are merely indicated roughly in FIG. 1 but which are illustrated more precisely in FIG. 4. Above each shoulder the side-wall is continued by a wall portion 10.

Provided at the bottom of the insertable unit 5 are stays 11 which can pivot about spindles 12 and which in the normal position occupy the flattened-out position illustrated in FIG. 1. The free ends 13 engage behind guide rails 14 which take the form of simple angle irons secured to the side-walls 2 and 3 and extending from a point near shoulder 8 to a point near the middle of the base. FIG. 5 shows a stay 11 made of wire bent to the required shape, this stay being guided by its free ends 13.

The stays 11 are acted upon by the force of a spring, not illustrated, which swings them downwards and outwards. Thus, when the insertable unit 5 is raised, the free ends 13 slide outwardly along the guides 14 (dotted position shown in FIG. 2) and are automatically brought into the position in which the free ends 13 bear on the shoulders 8. The widest splayed position of the stays 11 is such that they occupy approximately the position illustrated in FIG. 2 in which the free ends are located at points where the shoulders 8 merge with the wall portions 10. In this position the entire insertable unit is readily accessible, and it can be inspected and repaired. Oil dripping from the work-performing part 6 passes directly back into the casing 1.

The height of the wall portions 10 is such that, in the inspection position, they overlap the insertable unit 5 to a certain extent, so that abutments 15 are provided against lateral displacement of this insertable unit. In the abutting position the free end 13 of the opposite stay 11 occupies a position exactly above the guide 14. By means of a slight tilting movement this free end 13 can be inserted into the guide. If the insertable unit 5 is then moved against the opposite abutment 15, the free end 13 of the other stay 11 can also be brought into its associated guide 14. When the insertable unit 5 is lowered, the stays 11 are then automatically returned into the flattened out position illustrated in FIG. 1.

Provided on the control part 7 are two handles 16 with the aid of which the insertable unit 5 can be con-

veniently raised. These handles are extensions of a swingable cover 17 that extends into the central plane, and that can be brought into the position 17', shown in dash-and-dot lines, for the purpose of inserting plug-in printed-circuit boards 18. In the withdrawn position however, the swingable cover holds these push-in boards firmly between its lower face and the other frame 19. It must be secured in this position by means of a strong stud or other locking device 20. The positions of other components 21 of the control part 7 are merely indicated in an approximate manner.

As shown in FIG. 4, an opening 22 is provided in the wall portion 10 above the shoulder 8, the size of this opening being such that a multiple contact plug 23 can be passed through it. The opening 22 is closed by a cover plate 24 in which are provided bushes 25 through which cables 26 can be passed in a water-tight manner. The cover plate 24 is secured to the side-wall 2 by means of screws 27 which extend into projections 28.

Before the insertable unit 5 is removed from the casing 1, the cover plate 24 can be unscrewed and removed together with the multiple contact plug. The space above the shoulders can therefore be completely occupied by the control part 7. When the insertable unit is in the inspection position, the presence of the opening 22 enables the stay resting on the shoulder 8 also to be pushed back into the guide 14 by hand.

I claim:

1. Electrical apparatus comprising an upwardly open casing having an internal shoulder, an assembly located within said casing and movable from a position fully inserted in said casing to a position withdrawn from said casing, comprising an oil cooled lower unit and an upper control unit, said upper unit engaging said casing shoulder when said assembly is in its fully inserted position in said casing, internal guide means in said casing, strut means having ends connected to the lower end of said lower unit and having portions thereof engageable with said guide means, said portions of said strut means being engageable with said internal shoulder of said casing when said assembly is in said position withdrawn from said casing.

2. Electrical apparatus according to claim 1 wherein said strut means are pivotally connected to said lower unit and collapse to a horizontal position when said assembly is in its fully inserted position.

3. Electrical apparatus according to claim 2 wherein said guide means are generally vertically extending rails attached to the internal walls of said casing.
